UNITED STATES PATENT OFFICE

110,882

DESIGN FOR A JAR

Frasier Smith, Wheeling, W. Va., assignor to Hazel-Atlas Glass Company, Wheeling, W. Va.,
a corporation of West Virginia

Application June 25, 1938, Serial No. 78,075

Term of patent 14 years

To whom it may concern:

Be it known that I, Frasier Smith, a citizen of the United States, residing at Wheeling, in the county of Ohio and State of West Virginia, have invented a new, original, and ornamental Design for a Jar, of which the following is a specification, reference being had to the accompanying drawing, forming part thereof.

The figure is a perspective view of the jar showing my new design.

I claim:
The ornamental design for a jar, as shown.

FRASIER SMITH.
